SAFETY RAZOR HEAD GUARD

Ted L. Ferrier, Jr., P.O. Box 1451, Dallas, Tex. 75221

Filed May 26, 1971, Ser. No. 147,279

Term of patent 14 years

Int. Cl. D28—03

U.S. Cl. D95—3 A

Fig. 1

Fig. 2

Fig. 3

Fig. 4

Fig. 6

Fig. 5

Fig. 7

FIG. 1 is an isometric view from above and to one side of a safety razor head guard, showing my new design;

FIG. 2 is an isometric view from above and to the opposite side of the guard;

FIG. 3 is an isometric view from the bottom and to one side of the guard;

FIG. 4 is an isometric view from the top and one side of the end opposite FIG. 1;

FIG. 5 is a side elevation of the guard;

FIG. 6 is an isometric view from below and to one side with the two jaws partly opened; and

FIG. 7 is an isometric view from below and to one side with two jaws closed.

I claim:

The ornamental design for a safety razor head guard, substantially as shown.
